UNITED STATES PATENT OFFICE.

FRANCIS H. CRAFTS, OF WILLIAMSPORT, PENNSYLVANIA.

HAT.

SPECIFICATION forming part of Letters Patent No. 338,584, dated March 23, 1886.

Application filed September 12, 1884. Serial No. 142,880. (No model.)

To all whom it may concern:

Be it known that I, FRANCIS H. CRAFTS, a citizen of the United States, residing at Williamsport, in the county of Lycoming and State of Pennsylvania, have invented certain new and useful Improvements in Hats, of which the following is a specification, reference being had therein to the accompanying drawings.

10 Figure 1 is a perspective view of a hat having my improvement applied to its crown. Fig. 2 is a sectional view through Fig. 1, taken in the vertical plane of a row of perforations.

This invention relates to hats and caps; and 15 my object is to improve such head-wear by perforating its crown and employing, in connection with the perforations, cords, ribbons, tapes, or strips of any suitable material or color interwoven with said perforations and exposed to view on the outside of the crown 20 of the hat or cap, whereby I combine, in a neat and handsome manner, ornamental figures, with ventilating-apertures disposed over a large surface of the crown, as will be fully 25 understood from the following description, when taken in connection with the annexed drawings.

I have represented in the annexed drawings a round hat, which is of that kind usually 30 made of stiffened felted material that is practically air-proof. Such hats have been provided with a perforation on each side of and sometimes through the center of the crown, for the purpose of ventilation; but the ventilation 35 is exceedingly limited, and consequently persons wearing such hats frequently complain of headaches and loss of hair.

It is the object of my invention to remedy 40 this evil by allowing perfectly free ventilation, and at the same time to stiffen the crown and neatly ornament it.

A designates the crown of a hat known in the trade as a "Derby," and B is the rim thereof. E is a partition between the holes *a*. 45 These hats are usually made of a material which is impervious to air, and for the purpose of ventilation their crowns have been perforated, as above stated; but my invention is applicable to hats or caps made of any material or of any shape.

By reference to the drawings it will be seen that I make rows of perforations *a* through the external crown, A, and also through the lining C, and that I so dispose said perforations that by employing a fancy cord, D, of less size than the perforations and interlacing this cord therewith I produce an effect similar to embroidery or other ornamental work, which is exposed to view on the exterior surface of the hat.

In applying the cords, ribbons, embroidery, or strips of any suitable color or material, I pass them successively through the material of the crown, and also through the lining. I thus unite the lining to the crown, and at 55 same time retain the perforations through the two fabrics coincident with each other, thereby insuring free ventilation.

In the drawings the perforations are disposed in two rows, running from front to rear 70 of the upper part of the crown, and the cords D are interlaced to form diamonds or squares; but I do not confine my invention to such a disposition of the perforations and cords, as any other design may be produced and the 75 same result obtained. For instance, rows of perforations may be made to encircle the sides of the crown of a Derby or other style of hat, and the cords interlaced therewith in any fanciful manner.

In practice the perforations *a* may have eyelets applied to them, which may be made highly ornamental.

This invention is equally applicable to ladies' hats, and can be used to great advantage 85 upon them.

I am aware that hats have been made with a hole in the crown, with holes on opposite sides, and also of open-work. Furthermore, I am aware that it is old to provide the bosom 90 of a shirt with holes, and to lace the shirt up the front with a cord. I therefore disclaim the broad idea of lacing and the broad idea of perforating a hat; but

What I deem to be new, and desire to secure 95 by Letters Patent, is—

1. The combination of the hat A, provided with a series of perforations, *a a*, separated by a partition, E, extending nearly across the surface of the crown of the hat, with the cord 100

D, interlaced throughout the perforations a, thus forming a configuration upon the hat and a means of identification, substantially as set forth.

- 5 2. The combination of the perforated hat A and the crown-lining C, which is correspondingly perforated and placed in the hat, so that the perforations in the lining will register with those in the hat, with the cord D, interlaced
10 through the perforations in the hat and lining, thus securing them together and preventing

the sagging of the latter, and also keeping open the holes and facilitating the free circulation of air through the interior of the hat-crown, substantially as set forth.

In testimony whereof I affix my signature in presence of two witnesses.

FRANCIS H. CRAFTS.
